US00D965612S

(12) **United States Design Patent** (10) **Patent No.:** **US D965,612 S**
Stewart (45) **Date of Patent:** **** Oct. 4, 2022**

(54) **PORTION OF A DISPLAY SCREEN WITH A GRAPHICAL USER INTERFACE**

(71) Applicant: **Hoffmann-La Roche Inc.**, Little Falls, NJ (US)

(72) Inventor: **Kevin Adam Stewart**, Dundee (GB)

(73) Assignee: **Hoffmann-La Roche Inc.**, Little Falls, NJ (US)

(**) Term: **15 Years**

(21) Appl. No.: **29/831,071**

(22) Filed: **Mar. 17, 2022**

CLAIM

The ornamental design for a portion of a display screen with a graphical user interface, as shown and described.

DESCRIPTION

The single view is a front view of a portion of a display screen with a graphical user interface.

The broken lines showing a portion of a display screen form no part of the claimed design. The remaining broken lines showing text and portions of the graphical user interface form no part of the claimed design.

1 Claim, 1 Drawing Sheet
